UNITED STATES PATENT OFFICE.

HENRY SCHLACHTER, OF BEATRICE, NEBRASKA, ASSIGNOR TO DEMPSTER MILL MANUFACTURING CO., OF BEATRICE, NEBRASKA, A CORPORATION OF NEBRASKA.

WINDMILL.

Application filed August 5, 1921. Serial No. 489,988.

To all whom it may concern:

Be it known that I, HENRY SCHLACHTER, a citizen of the United States, residing at Beatrice, in the county of Gage and State of 5 Nebraska, have invented new and useful Improvements in Windmills, of which the following is a full, clear, concise, and exact description, reference being had to the accompanying drawing, forming a part of this 10 specification.

My invention relates to windmills.

One of the objects of my invention is to provide an improved oiling system for windmills, whereby all of the frictional parts will 15 be thoroughly automatically lubricated.

Further objects will appear from the detailed description to follow and from the appended claims.

In the drawings in which an embodiment 20 of my invention is shown—

Fig. 1 is a top plan view showing the main frame with an oil reservoir, part of the wind-wheel and transmission between the wind-wheel and pump-rod, the cover for the 25 oil receptacle being removed;

Fig. 2 is a vertical sectional view along the line 2—2 of Fig. 1;

Fig. 3 is a section substantially on the line 3—3 of Fig. 1;

Fig. 4 is an enlarged plan view of the rocker-arm;

Fig. 5 is a sectional view showing the oil dipper;

Fig. 6 is a section on the line 6—6 of Fig. 35 2, showing the main crank-shaft bearing;

Fig. 7 is a plan view of the lower half of the outer crank-shaft bearing; and

Fig. 8 is a perspective view of the lower 40 half of the outer bearing showing the means for scraping the oil from the shaft.

The construction shown in the drawings comprises a wind-wheel 10, (the hub alone being shown) a pump rod 11, transmission 45 12 between the wind-wheel 10 and pump-rod 11, and a main frame 13 for supporting the wind-wheel 10 and transmission 12, and for affording a suitable oil reservoir for supplying oil to the transmission 12.

In the particular construction shown a 50 vane 14 is provided for causing the wind-wheel 10 to be presented in proper position

with respect to the direction of the wind, although my invention is applicable to vaneless wind-mills.

The transmission 12 comprises a crank-shaft 15 on which the wind-wheel 10 is mounted, a pitman 16 (Fig. 3) having one end connected to the crank portion of the crank-shaft 15, a rocker-arm 17 to which the other end of the connecting rod 16 is pivoted, and a pair of lift-rods 18 having their lower ends pivotally connected to the rocker-arm 17, and their upper ends secured to the pump-rod 11. The rocker-arm is pivotally mounted on a pin 19. The upper ends of the lift-rods 18 are rigidly secured to the pump-rod 11 by means of bolts 20. This rigid connection here is permissible because the motion of the lift-rods 18 is so nearly rectilinear that a pivotal connection 60 between the lift-rods and pump-rod is not necessary.

As previously intimated, the main frame 13 provides an oil reservoir for oiling the transmission. The frictional parts which are oiled from this reservoir are as follows: The main bearing for the crank-shaft at 21; the outer bearing for the crank-shaft at 22; the inner bearing for the crank-shaft at 23; the pivotal connection between the crank-shaft and the connecting rod at 23^a; the pivotal connection between the connecting rod and the rocker-arm 17 at 24; the pivotal mounting of the rocker-arm at 19; and the pivotal connection between the rocker-arm 70 and the lift rods at 25. The oil level in the reservoir may vary from about the upper line indicated at A to the lower line indicated at B. If the oil reservoir is quite full the frictional parts at 19, 24 and 25 will be 80 practically immersed in the oil. The frictional parts at 21, 22, 23 and 23^a are supplied with oil dipped up from the reservoir by means of a revolving dipper 26 (Fig. 5). The dipper 26 scoops up the oil from the oil reservoir and delivers it to an oil receptacle 27 from whence it flows along the shaft 15 to the outer bearing 22, and thence back to the reservoir. Oil also drains from the receptacle 27 along the crank portion of the 90 crank-shaft to the crank-pin 23^a and follows along the crank to the inner bearing 23, 95

the line of flow of the oil dipped up by the dipper 26 being indicated diagrammatically by the arrow lines C and D.

The construction is also made such that 5 even when the oil level drops as far as the level indicated at B (which is below the pivot-pin 19 and the lowest portion of the path of travel of the dipper 26) all of the frictional parts referred to will still be supplied with oil. The frictional parts at 24 and 25 will still dip into the oil at the lower part of their travel, and the rocker-arm 17 is provided with channels 28 in its upper portion, which receive oil when the rocker-arm 15 is in its lowermost position, and deliver the oil thus received to the pin 19 when the rocker-arm is in its raised position, the oil flowing downwardly along these channels, and being delivered to an opening 29 (Figs. 3 and 4) in the hub of the rocker-arm and thus reaching the pivot pin.

In order that the dipper 26 may still be supplied with oil even when the oil level is low, an auxiliary oil pocket 30 is provided (Fig. 3) into which the dipper 26 dips, this auxiliary oil pocket 30 being kept supplied with oil splashed up by the rocker-arm 17.

I will now describe in detail the circulation of the oil from the oil receptacle 27 to the bearings 21 and 22, and thence back to the oil reservoir. In order to provide for the flow of oil from the receptacle 27 (to which it is delivered from the dipper 26) along the shaft 15 to the outer bearing 22, the cap 31 for the bearings 21 and 22 (Figs. 2 and 6) is provided with a channel 32, along which the oil flows to the outer bearing 22. The oil is confined in the channel 32 by the crank-shaft 15 so that it is compelled to flow along the shaft to the outer bearing. In order to assist the oil in its travel along this channel, a floating bar 33 may be provided, located in the channel 32, and resting on the shaft 15. This bar may be of wood, and rests lightly 45 on the shaft, and assists the oil in traveling along the shaft, also tending to prevent the oil from being carried around with the shaft.

In order to return the oil from the bearing 22 to the oil reservoir, an inclined channel 50 34 is provided in the main frame 13, this channel running underneath both of the bearings 21 and 22, and serving to drain the oil back into the oil reservoir.

In order to prevent oil from escaping at 55 the outer end of the bearing 22, the lower bearing member 35 is provided with a scraper portion 36, of substantially V-shape, which scrapes the oil from the shaft 15, at this point, and the oil thus scraped off, drops 60 down into the channel 34 and flows back into the reservoir.

In further explanation of the drawings, it is stated that a brake 37 is provided for the wind-wheel 10 which is automatically applied when the wind-wheel is thrown out of

gear. This construction, however, forms no part of my present invention, but is shown and mentioned simply for the sake of completeness.

An extra connection between the rocker-arm 17 and connecting pitman 16 is provided at 38, which may be used in case the load on the mill is too great to use the connection at 24.

A cover 39 is provided for the oil reservoir, which cover may be of sheet metal, having a sort of hinged connection at 40 with the reservoir, and having a detachable connection at 41 with the oil reservoir, which can be readily released to allow the cover to be swung upwardly about the pivot at 40. The detachable connection at 41 may comprise an eye-bolt 42, connected at 43 to the cover, and lying in a slotted lug 44, formed integral with the main frame casting. To release, the nut 45 is loosened, the eye-bolt 42 is swung outwardly to free it from the slotted lug 44, and the cover can then be tilted up to afford access to the oil reservoir and the mechanism therein. It will be noted that the pump-rod 11 operates through a sort of tubular passage way 46 extending up to and partitioned off from the oil reservoir, and that the arms of the rocker 17 straddle this tubular passage way, so that the arms 18 will lie in substantially vertical position parallel to the pump-rod 11, so as to lift directly upward on the pump-rod.

What I claim as new, and desire to secure by Letters Patent of the United States, is:

1. In a windmill the combination of a wind wheel; a main frame having an oil reservoir located therein; a vertical oil-tight tubular passage-way through the oil reservoir; a wind wheel driving shaft, a rocker arm located within the oil reservoir below the driving shaft; pitman connections between the driving shaft and the rocker arm; suitable connections from the forward end of the rocker arm with the pump rod for the purpose of operating same through the oil-tight passage-way.

2. In a windmill the combination of a wind wheel; a main frame having an oil reservoir located therein; a driving shaft operated by the wind wheel; a rocker arm located within the oil reservoir and below the driving shaft in such manner that on the downward stroke of the rocker arm the forward end will dip into the oil in the reservoir and on the upward stroke it will carry the oil upward lubricating other frictional parts; pitman connections between the driving shaft and rocker arm; lifting bars having oscillating connections at their lower end with the rocker arm and connections at their upper end with the pump rod.

3. In a windmill the combination of a wind wheel; a main frame having an oil reservoir located therein; a driving shaft

erated by the wind wheel; a rocker arm located within the oil reservoir and below the driving shaft; pitman connections between the drive shaft and rocker arm; suitable connections from the outer end of the rocker arm connecting same with the pump rod of the windmill.

4. In a windmill the combination of a wind wheel; a main frame having an oil reservoir located therein; a driving shaft; a rocker arm located within the oil reservoir and below the driving shaft; pitman connections between the drive shaft and rocker arm.

5. In a windmill the combination of a wind wheel; a main frame having an oil reservoir located therein; a driving shaft operated by the wind wheel; a rocker arm located within the oil reservoir and below the driving shaft in such manner that on the downward stroke of the rocker arm the forward end will dip into the oil in the reservoir, and on the upward stroke it will carry the oil upward lubricating other frictional parts; pitman connections between the driving shaft and rocker arm; lifting bars having oscillating connections at their lower end with the rocker arm and rigid connections at their upper end with the pump rod.

6. In a windmill the combination of a wind wheel; a main frame having an oil reservoir located therein; a driving shaft; a rocker arm located within the oil reservoir and below the driving shaft; an oil dipper attached to the driving shaft in such manner that when the driving shaft revolves the dipper will carry the oil up, emptying it into a receptacle, from which it will flow along the main drive shaft oiling the frictional parts of said shaft and shaft bearings; the outer bearing of the main shaft having suitable device at the outer end of same for wiping the oil off of the shaft; an opening below the top of the main shaft through which the oil will return by gravity to the reservoir.

7. In a windmill the combination of a wind wheel; a main frame having an oil reservoir located therein; a driving shaft; a rocker arm located within the oil reservoir and below the driving shaft; an oil dipper attached to the driving shaft in such manner that when the driving shaft revolves the dipper will carry the oil up emptying it into a receptacle, from which it will flow along the main drive shaft oiling the frictional parts of said shaft and shaft bearings, the outer bearing of the main shaft having a V-shaped device at the outer end of same for wiping the oil off of the shaft; an opening below the top of the main shaft through which the oil will return by gravity to the reservoir.

8. In a windmill the combination of a

wind wheel; a main frame having an oil reservoir located therein; a rocker arm located within the oil reservoir; a driving shaft located above the rocker arm; an upper bearing cap for the driving shaft, arranged at one end with an oil receptacle to receive oil for oiling the shaft bearings; means for elevating the oil from the oil reservoir to this receptacle, from which receptacle the oil will flow along the top of the drive shaft; suitable device at the outer bearing for wiping off the oil from the shaft; a passage-way below the top of said drive shaft through which the oil will return to the oil reservoir.

9. In a windmill the combination of a wind wheel; a main frame having an oil reservoir located therein; means for transmitting the rotary motion of the shaft to a reciprocating motion of the pump rod; a cap being the upper bearing of the driving shaft, having an oil receptacle at its inner end and a grooved recess in the upper portion of same, making a free passage for the transmission of the oil along the top of the shaft; an oil dipper attached to the driving shaft in such manner that as the driving shaft revolves this dipper will convey the oil upwards depositing same in the receptacle on the end of the cap bearing; the outer bearing of the driving shaft having a V-shaped device for wiping the oil off the shaft; a passage-way below the top of the shaft for returning the oil to the reservoir.

10. In a windmill the combination of a wind wheel; a main frame having an oil reservoir located therein; a rocker arm located within the oil reservoir; a driving shaft located above the rocker arm; an upper bearing cap for the driving shaft, arranged at one end with an oil receptacle to receive oil for oiling the shaft bearings; means for elevating the oil from the oil reservoir to this receptacle, from which receptacle the oil will flow along the top of the drive shaft; a passage-way below the top of said drive shaft through which the oil will return to the oil reservoir.

11. In a windmill the combination of a wind wheel; a main frame having an oil reservoir located therein; a drive shaft; a rocker arm below the drive shaft; a suitable connection between said drive shaft and rocker arm; an oil dipper operated by the drive shaft in such a manner that as the drive shaft revolves the dipper will carry the oil upward depositing it in a receptacle from which it flows to the main shaft bearing; feeding mechanism whereby the oil is fed outward along the drive shaft; a passage-way below the top of the said drive shaft for returning the oil to the oil reservoir.

12. In a windmill the combination of a wind wheel; a main frame for supporting

- same having a driving shaft; an oil reservoir located below the said shaft and within said frame; a rocker arm located within said oil reservoir; pitman connections between the rocker arm and the crank shaft; lifter bars having oscillating connections to the forward end of said rocker arm; the upper end of said lifting bars being connected with the pump rod by suitable connections.
- 10 13. A windmill construction comprising a wind wheel; a crank-shaft on which said wheel is mounted; a pump rod; an oil reservoir having a partitioned passage-way therethrough for said pump rod; a rocker member in said oil reservoir, having a pair of arms straddling said passage-way; a pair of links, one on each side of said passage-way, connected to said pump-rod, and pivotally connected to said rocker arms respectively,
- 15 20 the swinging ends of said rocker arms being movable below the oil in said reservoir; a connecting rod having one end connected to said crank, and the other extending between said arms and pivotally connected thereto.
- 25 14. A wind-wheel; a crank-shaft on which said wheel is mounted; a crank-shaft bearing for said crank-shaft; a main oil reservoir; a rocker arm in said oil reservoir; a pump-rod; transmission between said crank-shaft and rocker arm, and between said rocker arm and pump-rod; an auxiliary oil reservoir; an oil dipper mounted on said crank-shaft for supplying oil to said shaft bearing, said oil dipper dipping into said auxiliary reservoir, said rocker arm dipping into said main reservoir, and serving to supply oil into said auxiliary reservoir from said main reservoir.
- 30 15. A wind-wheel; a crank-shaft on which said wheel is mounted; a crank-shaft bearing for said crank-shaft; a main oil reservoir; a rocker arm in said oil reservoir; a pump-rod; transmission between said crank-shaft and rocker arm, and between said rocker arm and pump-rod; an auxiliary oil reservoir; an oil dipper mounted on said crank-shaft for supplying oil to said shaft bearing, said oil dipper dipping into said auxiliary reservoir, said rocker arm dipping into said main reservoir, and serving to supply oil into said auxiliary reservoir from said main reservoir.
- 35 40 16. A windmill construction comprising a wind wheel; a crank-shaft on which said wheel is mounted; a crank-shaft bearing for said crank-shaft; a main oil reservoir; a rocker arm in said oil reservoir; a pump-rod; transmission between said crank-shaft and rocker arm, and between said rocker arm and pump-rod; an auxiliary oil reservoir; an oil dipper mounted on said crank-shaft for supplying oil to said shaft bearing, said oil dipper dipping into said auxiliary reservoir, said rocker arm dipping into said main reservoir, and serving to supply oil into said auxiliary reservoir from said main reservoir for lubricating purposes.
- 45 50 55 17. A windmill construction comprising a wind wheel; a crank-shaft on which said wheel is mounted; a pump rod; an oil reservoir having a partitioned passage-way therethrough for said pump rod, a rocker member in said oil reservoir having a pair of arms straddling said passageway; a pair of links, one on each side of said passage-way connected to said pump rod, and pivotally connected to said rocker arm respectively, the swinging end of said rocker member being movable below the oil in said reservoir; and a pitman having one end connected to said crank-shaft, and the other connected to said rocker member.
18. A windmill construction comprising a wind-wheel; a crank-shaft on which said wheel is mounted; a pump rod; transmission mechanism between said crank-shaft and pump rod comprising a pitman pivotally connected to said crank-shaft, and extending downwardly therefrom, a rocker member below said crank-shaft to which the lower end of the pitman is pivotally connected, and a link having its lower end connected with said rocker member and the upper end connected with said pump rod and an oil reservoir in which said rocker member operates.
19. A windmill construction comprising a wind-wheel, a crank shaft driven by said wind-wheel, a pump rod, transmission mechanism between said crank shaft and pump rod comprising a pitman pivotally connected to said crank shaft and extending downwardly therefrom, a rocker member below said crank shaft to which the lower end of said pitman is connected, a link having its lower end connected with said rocker arm and its upper end connected with said pump rod, and an oil reservoir in which said rocker member operates.
